[57] CLAIM

The ornamental design for a combined winch mount and front end guard, as shown and described.

DESCRIPTION

FIG. 1 is a rear perspective view of a combined winch mount and front end guard showing my new design;
FIG. 2 is a front elevational view thereof;
FIG. 3 is a top plan view thereof;
FIG. 4 is a side elevational view thereof looking from the left side of FIG. 3; and
FIGS. 5 and 6 are cross sectional views thereof taken along lines 5—5 and 6—6 of FIG. 1.

FIG. 1.

FIG. 2.

FIG. 3.

FIG. 5.

FIG. 4.

FIG. 6.
